LIQUID PETROLEUM GAS DISTRIBUTING
SYSTEM

James B. Green, Sarasota, Fla.

Application April 24, 1933, Serial No. 667,725

1 Claim. (Cl. 137—78)

This invention relates to a method of and means for distributing liquid petroleum gases, such as propane, the general object of the invention being to provide means whereby the 5 liquid can be delivered from one tank to another without the use of pumps and other mechanical means.

This invention also consists in certain other 10 features of construction and in the combination and arrangement of the several parts, to be hereinafter fully described, illustrated in the accompanying drawings and specifically pointed out in the appended claim.

In describing the invention in detail, reference 15 will be had to the accompanying drawings wherein like characters denote like or corresponding parts throughout the several views, and in which:—

Figure 1 is a diagrammatic view showing how 20 the invention is carried out.

Figure 2 is a view partly in section and partly 25 in elevation, showing the receiving or storage tank and the pipes for connecting the same with the delivery tank.

Figure 3 is a detail sectional view showing how 30 a faucet on a pipe on the delivery tank is connected to a valve of a pipe leading to the storage tank.

In these drawings, the numeral 1 indicates the 35 receiving or storage tank for supplying stoves or other heating units of a building A with gas. A portion of the pipe line leading from the tank into the building is shown at 2 and contains the valve 3 and the pressure regulator 4. This tank is also supplied with a gauge, the tube through which a part of the gauge passes being shown at 5 and the float at 6. Figures 1 and 2 show the storage tank located underground and these figures also 40 show a pipe 7 passing from a point adjacent the bottom of the tank through the tank to a point above the ground where the upper end of the pipe is connected to a shut-off valve 8. A second pipe 9 has its lower end in communication with the top of the tank and its upper end is connected to 45 a shut-off valve 10.

The supply tank is shown at 11 and Figure 1 shows this tank as carried by a truck 12. This 50 tank 11 has a short pipe 12' leading from its bottom part and a short pipe 13 leading from its top part, these pipes being connected with the valves 14 and 15. Flexible hose 16 and 17 lead from these valves 14 and 15 and have the faucets 18 and 19 connected to their lower ends. These 55 faucets are each formed with a flange 20 at its lower end which is beveled to engage a beveled seat at the upper end of a valve 8 or 10, as shown in Figure 3, a collar 21 being threaded to the upper end of the valve and engaging the flange for fastening the faucet to the valve, as also 60 shown in Figure 3.

Thus when the storage tank is to be refilled from the supply tank, it is simply necessary to make the connections between the faucets 18 and 19 and the valves 8 and 10, after which the valves 10, 19 and 15 are opened to permit the pressure 65 above the liquid levels in the two tanks to equalize and then the valves 14, 18 and 8 are opened so that the liquid in the tank 11 will flow into the tank 1 and the air and gases replaced by the liquid flowing into the tank 1 will flow into the 70 upper part of the tank 11 and thus replace the liquid flowing from said tank 11.

Attention is called to the fact that the pipe 7 extends below the liquid level in the tank 1 so that the inflowing liquid from the tank 11 flows 75 into the liquid in the tank 1, so that the inflowing liquid is not vaporized as it would be if delivered into the tank 1 above the liquid level and if the liquid was delivered to the tank 1 above the liquid level, there would be danger of freezing or stop- 80 ping of the inlet at the tank 1.

Thus the invention eliminates the use of pumps and the like for forcing the liquid from the supply tank into the storage tank and this invention makes it possible to refill the storage tanks on 85 premises of users very easily and quickly and at a greatly reduced cost to the consumer of this type of fuel.

It is thought from the foregoing description 90 that the advantages and novel features of the invention will be readily apparent.

It is to be understood that changes may be made in the construction and in the combination and arrangement of the several parts, provided 95 that such changes fall within the scope of the appended claim.

What I claim is:—

A gravity distributing system for volatile liquids comprising a storage tank and a portable elevated delivery tank, a pipe having its lower 100 end connected with the top of the storage tank, a valve at the upper end of said pipe, a second pipe passing through the top of the storage tank to a point adjacent the bottom thereof, a valve at the upper end of said second pipe, a pair of 105 short pipes, containing valves, one connected to the bottom of the delivery tank and the other to the top thereof above the liquid level therein, a hose connected to each short pipe, a faucet connected to the free end of each hose and means for detachably connecting each faucet to a first 110 mentioned valve.

JAMES B. GREEN.
